UNITED STATES PATENT OFFICE.

CARL M. CUMMINGS, OF DILLON, COLORADO.

ATTACHMENT FOR AUTOMOBILE CHAINS.

1,410,170.

Specification of Letters Patent. Patented Mar. 21, 1922.

Application filed November 21, 1921. Serial No. 516,764.

To all whom it may concern:

Be it known that I, CARL M. CUMMINGS, a citizen of the United States, residing at Dillon, in the county of Summit and State of Colorado, have invented certain new and useful Improvements in Attachments for Automobile Chains, of which the following is a specification, reference being had therein to the accompanying drawings.

10 This invention relates to an attachment for automobile chains, and more particularly to a fastening device for connecting the ends of anti-skid chains.

15 The object of the invention is the construction of a simple and efficient fastening device whereby the ends of an anti-skid chain can be quickly fastened together.

20 With this and other objects in view, my invention comprises certain novel combinations, constructions and arrangements of parts as will be hereinafter described, illustrated in the accompanying drawings, and more particularly pointed out in the appended claim.

25 In the drawings:

Figure 1 is a perspective view of my fastening device.

Figure 2 is a view in side elevation of the fastening device.

30 Figure 3 is a longitudinal, sectional view of the fastening device.

Figure 4 is a sectional view, taken on line 4-4, Fig. 2, and looking in the direction of the arrows.

35 Figure 5 is a sectional view, taken on line 5-5, Fig. 2, and looking in the direction of the arrows.

Figure 6 is a longitudinal, sectional view of another embodiment of the fastening device.

40 Referring to the drawings by numerals, 1 designates a casing that comprises a bottom 2 and parallel sides 3-3. The bottom 2 is cut away, at 4, leaving an opening in the bottom in which the flat spring 5 may move or "play". This spring 5 is coiled, at its inner ends, around pin 6, and its outer end is left free to move in a vertical plane between the sides 3 and in the opening formed 45 by cutting away the bottom 2, at 4. A lock lever 7 is provided with a straight, inner end 8 adapted to bear flat against spring 5 when lever 7 is in a closed position, as shown

in Figs. 1 and 2; lock lever 7 is rotatably mounted upon rivet or pin 9. The lever 7 is 55 outwardly-bowed, at 10, this bowed portion 10 registering with the notched portion 11 of the sides 3, into which notch 11 and bowed portion 10, and link 12 on one end of an anti-skid chain may be positioned 60 (Figs. 1 and 2). Another notched portion 11^a is formed upon sides 3 so as to allow the operator to more readily grasp the grip end 13 of lock lever 7.

A bolt 14 is positioned in one end of the 65 sides 3, and on the ends of the bolt 14, and against the outer faces of the sides 3 is fastened a link 15; link 15 being connected to one end of an anti-skid chain.

In the embodiment shown in Fig. 6, the 70 spring 5^a is formed integral with the bottom 2, but in other respects the fastening device is the same as illustrated in Figs. 1 to 5.

My device is simple to operate since all that is necessary is to connect the same by 75 means of bolt 14 to one of the end links of the chain, and then connect the other end of the chain, to the device, by placing link 12 over the lock lever and then forcing the link into the notch 11 of the sides 3 and at the 80 same time close the lock lever 7 down between the sides 3, the lock lever being held in position by reason of the spring 5 engaging the flat end 8 of the lock lever.

While I have described the preferred embodiments of my invention, and have illustrated the same in the accompanying drawings, certain minor changes or alterations may appear to one skilled in the art to which this invention relates, during the extensive 90 manufacture of the same and I, therefore, reserve the right to make such alterations or changes as shall fairly fall within the scope of the appended claim.

95 What I claim is:

As a new article of manufacture, a fastening device comprising parallel sides and a bottom, said bottom being cut away and leaving an open portion upon the casing, a pin upon the sides of said casing near the 100 bottom, a flat spring coiled at one end around said pin, and working in the open portion of the bottom, another pin on said sides near one end of the casing, a lock lever rotatably mounted on said last-mentioned 105 pin, said lock lever provided with a flat or

straight inner end adapted to bear against said flat spring, said lock lever provided with an outwardly-bowed portion and with a grip at its outer end, said sides of the casing provided with a plurality of notches one of said notches registering with the bowed portion of the lock lever when the lock lever is closed

upon the casing, said grip of the lock lever registering with the other notch of the casing, and detachable means on one end of the casing for fastening a link to the casing.

In testimony whereof I hereunto affix my signature.

CARL M. CUMMINGS.
